US0D1111812S

(12) **United States Design Patent** (10) Patent No.: **US D1,111,812 S**
(45) Date of Patent: ** Feb. 10, 2026

(54) **POD**

(71) Applicant: **The Cumulus Coffee Company**, New York, NY (US)

(72) Inventors: **Gordon D. Row**, Groton, MA (US); **Demetrio D. Anaya**, Somerville, MA (US); **Adam Michael Paskow**, New York, NY (US); **Nathan J. Tyrowicz-Cohen**, Arlington, MA (US); **Zachary H. Zieper**, Woburn, MA (US); **Meshulem Gelman**, New York, NY (US)

(73) Assignee: **The Cumulus Coffee Company**, New York, NY (US)

(**) Term: **15 Years**

(21) Appl. No.: **29/903,164**

(22) Filed: **Sep. 20, 2023**

(51) LOC (15) Cl. **07-06**

(52) U.S. Cl.

USPC **D7/400; D9/518; D9/428**

(58) **Field of Classification Search**

USPC D9/414, 416, 417, 419, 424, 428, 434, D9/435, 438, 440, 447, 454, 500, 501, D9/503, 516, 518, 519, 549, 763, 772, D9/779, 780, 902, 903, 906; D7/300, D7/302, 303, 305, 316, 317, 321, 397, D7/399, 400, 401, 602, 619.1, 667

CLAIM

The ornamental design for a POD, as shown and described.

DESCRIPTION

FIG. 1 is a front perspective view of a POD showing our new design;

FIG. 2 is a bottom perspective view thereof;

FIG. 3 is a right elevational view thereof;

FIG. 4 is a left elevational view thereof;

FIG. 5 is a front elevational view thereof;

FIG. 6 is a rear elevational view thereof;

FIG. 7 is a top elevational view thereof; and,

FIG. 8 is a bottom elevational view thereof.

1 Claim, 8 Drawing Sheets
